GRILLE ASSEMBLY

Edward L. Hart and Charles Melvin Moore, Philadelphia, Pa., assignors, by mesne assignments, to Philco Corporation, Philadelphia, Pa., a corporation of Pennsylvania

Application January 8, 1946, Serial No. 639,855

2 Claims. (Cl. 98—40)

1

A primary object of this invention is to provide a grille assembly wherein the grille element is mounted in the supporting structure for adjustment selectively into a plurality of differing operative positions, said assembly including means for retaining said element captive in the structure and for tensioning the element to prevent rattling.

More specifically, the invention contemplates an assembly wherein the supporting structure comprises a frame in which the grille element may be received in any one of a number of differing predetermined positions, together with means for retaining the grille element captive while permitting retraction of the element from the frame for reinsertion in another of the alternative positions.

The invention further contemplates an assembly of the aforesaid character wherein the said retaining means functions also as a means for tensioning the grille against rattling in the frame.

The invention resides also in certain novel structural details and arrangements hereinafter described and illustrated in the attached drawings, wherein,

Figs. 1, 2, 3, and 4 are fragmentary views in perspective showing a grille assembly in accordance with the invention, the grille element occupying different ones of the four possible positions of adjustment in the respective views;

Fig. 5 is an enlarged sectional view on the line 5—5, Fig. 4;

Fig. 6 is a fragmentary inverted plan view of the assembly as shown in Figs. 4 and 5, partially in section on the line 6—6 of the latter figure, and

Fig. 7 is a sectional view on the line 7—7, Fig. 5.

With reference to the drawings, wherein, for purposes of illustration only, the grille assembly has been shown in application to an air conditioning unit, the casing of said unit, constituting the supporting structure for the assembly, is indicated by the reference numeral 1. Set into this casing, and defining the edges of an aperture 2 therein, is a rectangular frame 3, said frame having an outwardly extending lip or flange 4, which overlies the edges of the casing 1 surrounding said aperture, and having at its inner end a peripheral inwardly extending flange 5 which forms a seat for a grille element 6. When thus seated, the grille element is, in effect, inserted in the aperture 2 and neatly fills the latter.

The grille element 6 comprises a series of louvres or vanes 7 which extend in parallel spaced relation across the element from one of the side

bars 6a to the opposite bar, and which are inclined to the plane of the grille so as to exert a directional or deflecting effect upon air propelled through the opening 2 from the interior of the casing. Obviously, the actual direction of such deflection will depend upon the position of the grille in the frame 3. When the grille is positioned as shown in Figures 4 and 5, the inclined louvres act to direct the outflowing air to the right, as indicated by the arrows in Figure 4. When the grille is adjusted through an angle of 90° in a clockwise direction, the air will be deflected downwardly as indicated in Figure 1. A further adjustment of the grille through another angle of 90° will cause the air to be deflected to the left as indicated in Figure 3; and in the fourth position, as shown in Figure 2, the air will be directed upwardly.

These adjustments of the grille may be effected by lifting the grille bodily from the frame 3 and reinserting it in the desired position. It is desirable, however, that means be provided for retaining the grille captive so that while it is possible to remove the grille from the frame to make the aforesaid adjustments, it cannot be entirely removed from the structure. To this end, the grille is attached at its inner side to a strip 8 of flexible material, preferably resilient in character for a purpose hereinafter set forth. In the present instance, the strip is composed of spring steel and is provided at its mid section with an aperture 9 for reception of a stud 11 which projects from the inner side of the grille and at the center of the latter. The stud 11 is threaded for reception of a nut 12, which preferably is of a self-locking character, whereby the grille is attached to the strip. In the present instance, the stud 11 is formed at the end of a metallic pin 13 which is forcibly inserted in a recess 14 in a knob 15 formed integrally with and at the center of the grille.

The ends of the strip 8 occupy positions, respectively, within metallic channel elements 16—16 which are secured by screws 17 to the casing 1, said casing being provided in its inner side and at points adjoining the edges of the aperture 2 with recesses 18 for reception of the said channels. One of the screws of each pair, namely that one which lies nearest to the edges of said aperture, passes through a slot 19 in the end of the strip 8 so that the strip in effect is secured at each end to the casing 1. By reason of the slots 19, the strip is afforded a certain limited longitudinal movement in the channels 16 with respect to the channels and to the casing. This

longitudinal movement is sufficient to permit the strip to assume a position, shown in broken lines in Figure 5, when the grille is lifted from the frame 3. Normally, the spring will assume the position shown in full lines in Figure 5 wherein it exerts a tension on the stud 11, tending to hold the grille 6 to its seat upon the flange 5 of the frame 4. Thus the strip 8 functions both to hold the grille captive in the supporting structure, while permitting retraction thereof for adjustment purposes as described, and to tension the grille to prevent rattling thereof in the frame due to vibration of the structure.

It will be noted by reference to Figures 5, 6, and 7 that the channels 16 which house the ends of the strip 8 are provided with flanges 21-21 which provide a bearing surface for the extremities of the strip and prevent the said extremities from contacting directly with the casing 1. Any wear that might develop by reason of the movements of the ends of the strip falls, therefore, upon the channels rather than upon the other elements of the structure. It will be noted also that the channels 16 extend beyond the edges of the casing 1 and that the frame 4 is channeled at the underside for reception of the projecting ends of the channels 16 as indicated at 22.

In operation, if it is desired to change the position of the grille in its frame, it is merely necessary to withdraw the grille bodily through the medium of the knob 15 to the position shown in broken lines in Figure 5. While in this retracted position, the grille may be rotated freely about the axis of the stud 11, such rotation being permitted by the aforescribed loose connection between the grille and the strip 8. The grille may then be replaced in the desired position wherein it is resiliently retained by action of the spring strip 8 as described.

We claim:

1. In a grille assembly, a structure including a frame of non-circular form, a grille fitted to and seating in the frame and receivable in the latter in a plurality of differing positions, a leaf spring spanning the inner side of the frame and

connected to the grille in a manner to permit angular movements of the grille with respect to the spring and to the structure into said differing positions, said spring bearing at its ends against the structure and exerting resilient pressure tending normally to retain the grille against its seat in the frame, and means for anchoring the spring in the structure, said means including a sliding connection between an end of the spring and the structure so as to permit retraction of the grille from the frame.

2. In a grille assembly, a structure including a frame of non-circular form, a grille fitted to and seating in the frame and receivable in the latter in a plurality of differing positions, a leaf spring spanning the inner side of the frame and connected to the grille in a manner to permit angular movements of the grille with respect to the spring and to the structure into said differing positions, said spring bearing at its ends against the structure and exerting resilient pressure tending normally to retain the grille against its seat in the frame, means for attaching the ends of the spring to the structure, said attaching means affording movement of the spring relative to the structure to an extent permitting retraction of the grille from the frame, and housing means embracing the said spring ends.
